DESIGN FOR A TEXTILE FABRIC

Aaron Levy, New York, N. Y.

Application March 20, 1939, Serial No. 83,694

Term of patent 3½ years

To all whom it may concern:

Be it known that I, Aaron Levy, a citizen of the United States of America, residing in New York city, in the Borough of Manhattan, county and State of New York, have invented a new, original, and ornamental Design for a Textile Fabric, of which the following is a specification, reference being had to the accompanying drawing, forming part thereof, wherein the figure is a plan view of a piece of textile fabric showing my new design.

The design consists of a series of lustrous stripes arranged in regular succession over the dulled surface of the fabric, each lustrous stripe being edged with a light and dark vein of contrasting color and inner veins of a dulled texture, as shown.

I claim:

The ornamental design for a textile fabric, substantially as shown and described.

AARON LEVY.
